(57) **CLAIM**

The ornamental design for a winch cover, as shown and described.

DESCRIPTION

FIG. 1 is a top, front and left perspective view of a winch cover showing our new design;

FIG. 2 is another perspective view of the winch cover;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines in FIGS. 1, 6, 7 and 8 are included for the purpose of illustrating environment and form no part of the claimed design.
